TAKE-UP APPARATUS

Duer C. Robson, Baltimore, Md., assignor to Western Electric Company, Incorporated, New York, N. Y., a corporation of New York

Application July 23, 1948, Serial No. 40,290

24 Claims. (Cl. 242—80)

1

This invention relates to takeup apparatus, and more particularly to apparatus for continuously reeling strands, such as insulated conductors.

In strand processing operations, such as in the extrusion of an insulated covering over a conductor and the vulcanization of the covering immediately after the extrusion operation, a strand usually is wound upon some type of holder, such as a reel, to facilitate storage or further handling of the strand. In the past, when the reel was filled with the strand and a new reel or the like had to be substituted therefor, or a switch was effected from one reel to another, it usually was necessary to shut down the processing apparatus during such a substitution or switching. Such interruptions of the process increased the cost of production of the strands, and, in the case of extrusion and vulcanization of insulated coverings upon conductors, the portions of the coverings remaining in the vulcanizing apparatus during the interruptions were overcured and had to be scrapped. Some continuously operable takeup apparatus have been proposed in the past, but this apparatus has not been entirely satisfactory.

An object of the invention is to provide new and improved takeup apparatus.

A further object of the invention is to provide new and improved apparatus for continuously reeling strands, such as insulated conductors.

Another object of the invention is to provide new and improved strand takeup apparatus for switching a strand from one takeup reel to another without interrupting the winding process.

A takeup apparatus illustrating certain features of the invention may include a pair of reels, means for rotating the reels, a snagger provided with a strand catching and gripping portion revolved with one of the reels, and means selectively operable for guiding a strand past one of the reels to the other reel into the path of the snagger so that the strand is caught by the snagger.

A complete understanding of the invention may be obtained from the following detailed description of an apparatus forming a specific embodiment thereof, when read in conjunction with the appended drawings, in which:

Fig. 1 is a fragmentary front elevation of an apparatus forming one embodiment of the invention;

Fig. 2 is an enlarged, fragmentary plan view showing a portion of the apparatus shown in Fig. 1;

Fig. 3 is an enlarged, front elevation of the portion of the apparatus shown in Fig. 2 with portions thereof broken away;

Fig. 4 is a vertical section taken along line 4—4 of Fig. 2;

Fig. 5 is an enlarged section taken along line 5—5 of Fig. 3;

2

Fig. 6 is an enlarged, elevation of a cutter forming a part of the apparatus;

Fig. 7 is an enlarged end elevation of the cutter shown in Fig. 6, and

Fig. 8 is an enlarged, fragmentary view of a snagger forming a part of the apparatus.

Referring now in detail to the drawings, a filamentary, conductive core 10, such as a copper or bronze wire, is advanced from one of two supply reels 12—12 by a dual capstan 14, and is pulled through an extruder 16, through a continuous vulcanizing tube 18 in tandem with the extruder 16, along a cooling trough 20, and over a guide sheave 22 by the dual capstan 14. The extruder 16 forms a vulcanizable covering 24 on the conductive core 10 and the covered core is introduced continuously into the vulcanizing tube 18. Steam under high pressure is fed into the vulcanizing tube 18 to vulcanize the covering 24 as it is advanced therethrough to produce an insulated conductor 26.

The conductor 26 is advanced from the capstan 14 to a continuous takeup unit 28, and is advanced over a guide sheave 32 of a distributor 34 either to a takeup mechanism 36 or to a takeup mechanism 38, which is similar to the mechanism 36 but rotates in an opposite direction. The sheave 32 is mounted rotatably on an arm 40 (Fig. 3) carried by a distributor head 42 (Fig. 2) supported slidably on a shaft 44 and a rod 46. The shaft 44 and the rod 46 are supported by slides 48—48 mounted slidably on guide rods 50—50 having racks 52—52 (Fig. 3) formed thereon. A reversible electric motor 60 (Fig. 2) carried with the slides 48—48 rotates a distributor screw 62 in either of two directions.

When the motor is actuated to rotate the distributor screw in one direction, the distributor screw moves the distributor head 42 toward a flange 63 of a reel 64 so that the sheave 32 is moved toward the flange 63 to distribute the conductor 26 upon the reel 64 mounted in the take up mechanism 36, which is rotated in a counterclockwise direction, as viewed in Fig. 3,

45 by means of a motor 65. When the distributor sheave 32 reaches its furthermost position, an actuating pin 66 carried by the distributor head 42 strikes an arm 68 of a limit switch 70 to reverse the direction of rotation of the motor 60 and the distributor screw 62, whereby the distributor screw moves the head 42 and the sheave 32 toward a flange 69 (Fig. 2) of the reel 64 to form another layer of the conductor on the takeup reel 64.

55 When the sheave 32 reaches its furthermost position near the flange 69, an actuating rod 71 strikes an arm 72 of a limit switch 74 to again reverse the direction of rotation of the motor 60 and the distributor screw 62. The actuator rods 66 and 71 are mounted slidably in bosses 76 and

78, respectively, formed on a plate 79 of the distributor head 42. The positions of the rods 66 and 71 may be adjusted by a thumb screw 80 extending through a tapped bore 82 in the plate 79 and tapped bores 86 and 88 formed in arms 90 and 92, respectively, which are rigidly secured to the actuating rods 66 and 71. Thus, the length of throw of the distributor may be adjusted as desired.

A hand wheel 94 is keyed to the shaft 44, 10 which carries two pinions, of which a pinion 96 (Fig. 3) is shown, on the ends thereof. The pinions 96—96 engage the racks 52—52 of the guide rods 50—50. The hand wheel 94 may be rotated to rotate the shaft 44 and the pinions 96—96 15 to move the slides 48—48 along the rods 50—50 to the right or to the left, as viewed in Fig. 3, thereby changing the position of the distributor sheave 32 with respect to the takeup mechanisms 36 and 38. A pivoted latch 104 may be actuated to lock the distributor 34 in any desired position on the guide rods 50—50. Normally, while the conductor 26 is being wound on the takeup mechanism 36, the distributor 34 is in the broken-line position thereof shown in Fig. 3, and the conductor 26 follows a path shown in broken lines to the reel 64. When the reel 64 is almost filled 20 the latch 104 is released and the hand wheel 94 is actuated to move the distributor 34 to the full-line position thereof. This causes the path of the conductor 26 as it leaves the distributor sheave 32 and advances to the reel 64 to change from that shown by the broken-line to that shown in full lines. The portion of this path of the conductor 26 between points A and B forms a chord with respect to flanges 109—109 of a reel 110 25 mounted in the takeup mechanism 38, which reel, when driven is rotated in a clockwise direction, as viewed in Fig. 3.

An electric motor 116 (Fig. 4) forming a part 40 of the takeup mechanism 38 then is energized to start the rotation of the reel 110. A centering cone 118 keyed to the reel 110 by a pin 119 and an arm 120 is rotated in a clockwise direction, as viewed in Fig. 3, by the motor 116, and a freely 45 rotatable centering cone 121 (Fig. 5) connected to the reel 110 by a pin 122 and an arm 123 is rotated by the reel. The centering cone 121 serves to rotate a guard 124 therewith when a manually operable clutch 125 is thrown into operative position. The clutch 125 serves to connect the cone 121 to the guard 124 through a shaft 127 connected rigidly to the cone and a sleeve 129 formed integrally with the guard 124.

The guard 124 carries an arm 126 pivotally thereon, and a snagger 128 having a snagging notch 130 formed therein is carried by the arm 126 and is designed to slide through a slot 131 formed in the guard 124. The arm 126 carries a follower 132 designed to ride in a cam slot 134 formed in a fixed bearing 136 as the arm 126 is rotated with the guard 124. As the cam follower 132 moves along the cam slot 134, the arm 126 is urged to position the snagger 128 further to the left, as viewed in Fig. 4, to a position extending over the inner flange 109 of the reel 110 shortly after the snagger passes the point "A" (Fig. 3). However, as the snagger passes point "A," the cam slot 134 acts to hold the snagger in such a position that it is not over the reel 110, and the snagger clears the conductor 26 whenever the conductor is near the flange of the reel as the snagger approaches the portion of the conductor 26 at the point "A."

When the distributor sheave 32 advances the 75

conductor 26, which subtends a portion of the flanges 109—109 of the reel 110, to a position in which the conductor is near the right hand flange of the reel, as viewed in Fig. 4, and the clutch 125 has been actuated to connect the guard 124 to the reel 110, the snagger clears the portion of the conductor at point A (Fig. 3), is moved over the conductor between the points "A" and "B," catches the portion of the conductor at point "B" in the notch 130 (Fig. 8) formed in the leading edge of the snagger and pulls the conductor downwardly, as viewed in Fig. 3. The takeup reel 64 continues to be rotated and to wind the conductor 26 thereon, and the portion of the conductor between the snagger and the reel 64 is moved downwardly.

The inrunning reel 64 and the snagger 128 move the portion of the conductor therebetween downwardly between blades 140—140 of a shear 142, and press the conductor hard against a presser bar 144 to press the bar downwardly, as viewed in Fig. 3, against springs 146—146 (Fig. 7). As the bar 144 is moved downwardly, it moves downwardly a pin 148 on which the blades 140—140 are pivotally mounted, and the pin moves downwardly relatively to pins 150—150 carried by a pivotally mounted carriage 152 to pivot the blades together to sever the conductor 26.

The blades 140—140 may be actuated as just described, or they may be actuated by pivoting the carriage 152 around pins 154—154 either in a clockwise direction or in a counterclockwise direction, as viewed in Fig. 7. When the carriage 152 is pivoted in a counterclockwise direction, cam followers 156—156 (Fig. 7) fastened to the presser bar 144 are pressed by a pair of cams, of which a cam 138 is shown, so as to move the bar 144 against the action of the springs 146—146 to close the blades 140—140. Thus, after the bar 144 is depressed sufficiently by the conductor 26 and the blades 140—140 dig into the covering 24 of the covered conductor 26, the blades 140—140 and the carriage are pulled either to the right or to the left, and the cutting action of the blades is augmented by the pivoting of the carriage 152 and the blades 140—140 carried therewith sever the conductor 26.

The snagger 128 continues to rotate with the reel 110, and the distributor 34 distributes the conductor 26 on the reel 110 as the snagger is rotated beyond the point B (Fig. 3) to somewhere near the point "C." When the snagger reaches the point C, the cam slot 134 (Fig. 4) moves the snagger back to a position in which it does not extend over the flange of the reel 110, and the snagger continues to hold the conductor so that the conductor is wound on the reel 110. This oscillation of the snagger back and forth over the end of the reel 110 occurs at every revolution of the reel 110 so that the snagger is sure to clear the portion of the conductor 26 being advanced to the reel 110. Thus, after the winding has been started on the reel 110 as described hereinabove, there is no danger of resnagging the conductor 26. The takeup mechanism 36 is provided with a snagger and its associated elements which are identical with those of the takeup mechanism 38 except that they are of opposite hand. The takeup mechanism 36 operates in the same manner as does the takeup mechanism 38 except that the mechanism 36 is a left hand mechanism, while the mechanism 38 is a right hand mechanism. After the reel 110 has been filled, the distributor 34 is moved to

its broken-line position and the above-described operation in connection with starting and winding of the conductor 26 on the reel 110 is conducted with the take-up mechanism 36 to shear the conductor and start the conductor on a reel substituted for the reel 64.

The motor 116 (Fig. 4) is mounted on a slide 170 mounted on a guideway 172, and a bearing 174 supporting the centering cone 118 also is carried by the slide 170. After the reel 110 has been filled and the conductor 26 is severed therefrom, the motor 116 is deenergized and a linkage 176 is moved so as to actuate a valve 178 to supply air under pressure to the right hand end of a cylinder 180, as viewed in Fig. 4, and to pivot a latch 182 secured rigidly to a shaft 184 out of a slot 188 formed in the slide 170 so that the slide may be slid to the left by a piston 190 fastened to the slide to free the reel 110 for removal. After an empty reel to be substituted for the reel 110 has been positioned between the centering cones 120 and 122, the linkage 176 is moved to actuate the valve 178 to supply air under pressure to the left end of the cylinder 180 and to permit the latch 182 to move into the slot 188 whenever the slot 188 is moved thereover. The piston then moves the slide 170 to mount the empty reel on the centering cones 120 and 122, and the latch moves into the slot 188 to latch the slide in an operative position.

Operation

The insulated conductor 26 is advanced over the sheave 32 of the distributor mechanism 34, which is in its broken-line position, as viewed in Fig. 3, to the reel 64 of the takeup mechanism 36, the motors 60 and 65 are started, and the distributor 34 distributes the conductor 26 in layers extending from flange to flange of the reel 64. When the reel 64 is almost filled, an operator of the apparatus releases the latch 104, and moves the distributor mechanism 34 to the left to its full-line position. The operator then starts the motor 116 (Fig. 2) to rotate the reel 110 in an inrunning direction with respect to the direction of rotation of the reel 64, and the distributor 34 continues to distribute the conductor evenly upon the reel 64.

When the reel 64 is filled, the operator actuates the clutch 125 (Fig. 4) to connect the guard 124 to the centering cone 121, which is driven by the reel 110. The arm 126 and the snagger 128 then are rotated with the reel 110 at the same speed of rotation as the reel 110, and the cam slot 134 moves the snagger 128 from a position at the edge of the right hand flange of the reel 110, as viewed in Fig. 4, to the position of the snagger 128 shown in Fig. 5 where the snagger has passed point A (Fig. 3) but has not yet come to point B. After the snagger is rotated past point C, the cam slot 134 moves it back to a position in which it does not extend beyond the inner flange of the reel 110. When the distributor sheave 32 moves the conductor 26 to the right hand flange of the reel 110, as viewed in Fig. 4, the snagger 128 catches the conductor 26 and moves the portion of the conductor between the snagger and the reel 64 between the blades 140—140 of the shear 142 and hard against the presser bar 144, which actuates the shear 142 to sever the conductor.

The snagger 128 continues to hold the newly formed end of the conductor 26 and carries it around the drum of the reel 110, and the distributor 34 distributes the conductor on that reel. After the several layers of the conductor have been

built up on the reel 110 so that the conductor is firmly attached to the reel 110, the clutch 125 (Fig. 4) is disengaged to disconnect the guard 124 from the centering cone 121 so that the rotation of the guard 132 and the snagger 128 is stopped. The end of the conductor held by the snagger 128 then is drawn from the notch 130 therein to free the conductor from the snagger.

10 The operator then stops the takeup mechanism 36, removes the filled reel 64 therefrom, and substitutes an identical empty reel for the reel 64. When the reel 110 is filled with the conductor 26, the distributor 34 is moved to its broken-line position, as shown in Fig. 3, so that a portion of the conductor 26 between the sheave 32 and the takeup reel 110 is in a plane chordally intersecting the flanges of the reel of the takeup mechanism 36 so that it may be snagged. The 15 switchover to the empty reel of the takeup mechanism 36 then is effected by a snagger and its associated elements forming part of the takeup mechanism 36, which are identical with the snagger 128 and its associated elements of the takeup mechanism 38.

20 The above-described takeup mechanism serves to continuously take up the conductor 26 without interruption in or slowing of operation so that the operation of the extruder 16 and the vulcanization is not even slowed down. The transfer from one takeup mechanism to the other is almost completely automatic inasmuch as the only manual effort necessary to make a transfer from one takeup reel mechanism to the other is to move the distributor mechanism 34 to the proper position, to start the idle takeup reel mechanism, to effect engagement of the clutch of the idle takeup mechanism and to disengage the clutch after the transfer has been made. There is no danger to an operator of the apparatus since the snaggers are covered and accidental contact therewith is prevented.

25 What is claimed is:

1. A takeup apparatus, which comprises a pair of reels, means for rotating the reels, a snagger provided with a strand-catching-and-gripping portion revolved with one of the reels, and means selectively operable for guiding a strand past one of the reels to the other reel into the path of the snagger.

30 2. A takeup apparatus, which comprises a rotatable takeup unit, a second rotatable takeup unit, means for rotating the units on parallel axes and for mounting the units in transversely aligned positions, means for guiding a strand past the first-mentioned takeup unit to the second-mentioned takeup unit, and a snagger carried with the first-mentioned takeup unit and movable from a position with respect to that unit in which the strand is not engaged thereby to a position in which the strand is snagged thereby.

35 3. A takeup apparatus, which comprises a pair of reels mounted in transverse alignment, a guideway extending transversely to longitudinal axes of reels, a guide mounted on the guideway for guiding a strand past one of the reels to the other reel when on one portion of the guideway and for guiding a strand past the last-mentioned reel to the other reel when on a second portion of the guideway, means carried by each of the reels for snagging a strand guided therewith, and selectively operable means for actuating the strand-snagging means.

40 4. A takeup apparatus, which comprises a pair

of reels mounted in transverse alignment, a guideway extending transverse to longitudinal axes of reels, a distributor traversable substantially parallel to the longitudinal axes of the reels and mounted movably on the guideway for guiding a strand past one of the reels to the other reel when on one portion of the guideway and for guiding a strand past the last-mentioned reel to the other reel when on a second portion of the guideway, a snagger carried by one of the reels for snagging a strand guided past that reel, a second snagger carried by the other reel for snagging a strand carried past that reel, and means for actuating the snaggers individually.

5. A takeup apparatus, which comprises a pair of rotatable takeup elements mounted in transverse alignment, a guideway extending transversely to axes of rotation of the takeup element, a guide mounted movably on the guideway for guiding a strand past one of the reels to the other reel when on one portion of the guideway and for guiding a strand past the last-mentioned reel to the other reel when on a second portion of the guideway, means for moving the guide from one of said portions of the guideway to the other portion thereof, means for holding the guide at the first-mentioned portion of the guideway, means for holding the guide at the second-mentioned portions of the guideway, means carried by each of the reels for snagging a strand guided therewith, individually operable means for actuating the strand-snagging means.

6. A takeup apparatus, which comprises a rotatable reeling element, a second rotatable reeling element, means mounting the reeling elements in transversely aligned positions for rotating the reeling elements selectively and simultaneously in inrunning directions, a rotatable arm mounted pivotally at one end of the first-mentioned reeling element, a snagger carried by the arm and extending substantially parallel to axis of rotation of the first-mentioned reeling element and radially outside that reeling element so that the snagger is projected over that reeling element when the arm is pivoted toward that reeling element, means operable selectively for connecting the snagger to the first-mentioned reeling element to revolve the snagger in a predetermined generally circular path beyond the radial limits of the first-mentioned reeling element, a distributor movable transversely to the axis of rotation of the reeling element for distributing a strand upon the second-mentioned reeling element and for guiding the strand to the second-mentioned reeling element in a plane chordally cutting said path of the snagger, and cam means for holding the snagger in a position beyond the near end of the first-mentioned reeling element as the snagger is moved past the portion of the strand entering the portion of the plane chordally intersecting the path of the snagger so that the snagger clears that portion of the strand for moving the snagger to a position extending over the near end of the first-mentioned reeling element after the snagger has been moved past the portion of the strand entering said portion of said plane and before the snagger has been moved to the portion of the strand leaving said portion of said plane and for holding the snagger in the position extending over the near end of the first-mentioned reeling element as the snagger is moved to and past the point at which the strand leaves said portion of the plane so that the snagger catches and grips

the strand as the strand is moved past the near end of the first-mentioned reeling element.

7. A takeup apparatus, which comprises a rotatable reeling element, a second rotatable reeling element, means mounting the reeling elements in transversely aligned positions for rotating the reeling elements in inrunning directions, a snagger rotatable with the first-mentioned reeling element and having a snagging portion extending substantially parallel to axis of rotation of the first-mentioned reeling element and radially outside that reeling element, means mounting the snagger for movement relative to the first-mentioned reeling element such that the snagging portion is projected over that reeling element when the snagger is moved toward that reeling element, the snagging portion of the snagger being revolved in a predetermined substantially circular path beyond the radial limits of the first-mentioned reeling element, a distributor for distributing a strand upon the second-mentioned reeling element and for guiding the strand to the second-mentioned reeling element in a plane chordally cutting the path of the snagger, means for holding the snagger in a position in which the snagging portion thereof is beyond the near end of the first-mentioned reeling element as the snagging portion is moved past the portion of the strand entering the portion of the plane chordally intersecting the path of the snagger so that the snagging portion clears that portion of the strand, and means for moving the snagger to a position in which the snagging portion extends over the near end of the first-mentioned reeling element after the snagging portion has been moved past the portion of the strand entering said portion of said plane and before the snagging portion has been moved to the portion of the strand leaving said portion of said plane and for holding the snagging portion in the position extending over the near end of the first-mentioned reeling element as the snagging portion is moved to and past the point at which the strand leaves said portion of the plane so that the snagging portion catches and grips the strand as the strand is moved past the near end of the first-mentioned reeling element.

8. A takeup apparatus, which comprises a pair of transversely aligned reels, means for rotating the reels, means for guiding a strand past one of the reels to the other reel, a snagger provided with a strand catching and gripping portion revolved with the reel past which a strand is guided, a cutter positioned between the snagger and the other reel, and means for projecting the strand catching and gripping portion of the snagger beyond the flange of the reel past which the strand is guided to catch and grip the strand, whereby the portion of the strand between the snagger and the reel to which the strand is guided is moved into engagement with the cutter and severed.

9. A takeup apparatus, which comprises a pair of transversely aligned reels, means for rotating the reels in inrunning directions, means for guiding a strand past one of the reels to the other reel, a snagger provided with a strand catching and gripping portion revolved with the reel past which a strand is guided, a shear positioned between the snagger and the other reel, and means for projecting the strand catching and gripping portion of the snagger beyond the flange of the reel past which the strand is guided to catch and grip the strand, whereby the portion of the strand between the snagger and the reel to which the strand is guided

strand is guided is moved into engagement with the shear and severed.

10. A takeup apparatus, which comprises a pair of reels mounted in transverse alignment, a guideway extending transversely to longitudinal axes of reels, a distributor mounted movably on the guideway for guiding a strand past one of the reels to the other reel when on one portion of the guideway and for guiding a strand past the last-mentioned reel to the other reel when on a second portion of the guideway, snaggers carried by each of the reels for snagging the strand guided theretofore, means for actuating the snaggers selectively, and means against which the strand is moved by either of the snaggers for severing the strand.

11. A takeup apparatus, which comprises a winding element, means for rotating the winding element, a snagger carried by one end of the winding element and movable from a position in which the snagger does not project over the winding element to a position in which the snagger does project over the winding element, and means for moving the snagger to the position thereof in which it projects over the winding element for a predetermined portion of the revolution of the snagger so that the snagger clears one portion of a strand guided chordally with respect to the path of the snagger and catches a second portion of the strand.

12. A takeup apparatus, which comprises a rotatable winding element, means for rotating the winding element, an L-shaped snagger carried pivotally by one end of the winding element and having a strand-snagging portion movable from a position in which that portion does not project the winding element to a position in which it does project over the winding element, means for guiding a strand in a plane chordal with respect to the path of the strand-snagging portion of the snagger, and means for holding the strand-snagging portion of the snagger in the position thereof in which it does not project over the winding element as that portion is moved past one portion of the strand and for projecting the strand-snagging portion of the snagger over the winding element as the strand-snagging portion approaches a second portion of the strand.

13. A takeup apparatus, which comprises a reel, means engaging one end of the reel for rotating the reel, reel-mounting means for engaging the other end of the reel and rotatable thereby, a snagger extending radially beyond the reel and carried by the reel-mounting means and movable from a position in which the snagger does not project over the more adjacent head of the reel to a position in which the snagger does project over the head of the reel, means for selectively connecting the snagger to the reel-mounting means for rotation therewith, and means for moving the snagger to the position thereof in which it projects over said head of the reel for a predetermined portion of the revolution of the snagger.

14. A takeup apparatus, which comprises a reel, means engaging one end of the reel for rotating the reel, reel-mounting means for engaging the other end of the reel and rotated thereby when the reel is rotated, a snagger carried by the reel-mounting means and movable from a position in which the snagger does not project over the more adjacent head of the reel to a position in which the snagger does project over that head of the reel, a clutch for connecting the snagger

to the reel-mounting means for rotation therewith, means for actuating the clutch, and means for moving the snagger to the position thereof in which it projects over said head of the reel for a predetermined portion of the revolution of the snagger when the snagger is rotated with the reel-mounting means.

15. A takeup apparatus, which comprises a rotatable reeling element, a second rotatable reeling element, means mounting the reeling elements in transversely aligned positions for rotating the reeling elements in inrunning directions, an arm carried with and mounted pivotally at the end of the first-mentioned reeling elements, a snagger carried by the arm and extending substantially parallel to axis of rotation of the first-mentioned reeling element and radially outside that reeling element so that the snagger is projected over that reeling element when the arm is pivoted toward that reeling element, said snagger being revolved in a predetermined circular path beyond the radial limits of the first-mentioned reeling element, a distributor adjustable transversely to the axis of rotation of the reeling element for distributing a strand upon the second-mentioned reeling element and for guiding the strand to the second-mentioned reeling element in a plane chordally intersecting the path of the snagger, means for holding the snagger in a position beyond the near end of the first-mentioned reeling element as the snagger is moved past the portion of the strand entering the portion of the plane chordally intersecting the path of the snagger so that the snagger clears that portion of the strand, means for moving the snagger to a position extending over the near end of the first-mentioned reeling element after the snagger has been moved past the portion of the strand entering said portion of said plane and before the snagger has been moved to the portion of the strand leaving said portion of said plane and for holding the snagger in the position extending over the near end of the first-mentioned reeling element as the snagger is moved to and past the point at which the strand leaves said portion of the plane so that the snagger catches and grips the strand as the strand is moved past the near end of the first-mentioned reeling element, and a cutter positioned outside the circular path of the snagger and in the path in which the portion of the strand between the snagger and the second-mentioned reeling element is moved by the snagger for severing the strand.
16. A takeup apparatus, which comprises a rotatable reeling element, a second rotatable reeling element, means mounting the reeling elements in transversely aligned positions for rotating the reeling elements in inrunning directions, a snagger carried with the first-mentioned reeling element at an end thereof and extending substantially parallel to axis of rotation of the first-mentioned reeling element and radially outside that reeling element, the snagger being projectable over the first-mentioned reeling element and being revolved in a predetermined circular path beyond the radial limits of the first-mentioned reeling element, a distributor movable transversely to the axis of rotation of the reeling element for distributing a strand upon the second-mentioned reeling element and for guiding the strand to the second-mentioned reeling element in a plane chordally cutting the path of the snagger, means for preventing snagging action of the snagger as the snagger is moved past the portion of the strand entering the portion of

the plane chordally intersecting the path of the snagger, means for actuating the snagger after it has been moved past the portion of the strand entering said portion of said plane and before the snagger has been moved to the portion of the strand leaving said portion of said plane and for holding the snagger in the position extending over the near end of the first-mentioned reeling element as the snagger is moved to and past the point at which the strand leaves said portion of the plane so that the snagger catches and grips the strand as the strand is moved past the near end of the first-mentioned reeling element, and a cutter positioned outside the circular path of the snagger in the path in which the portion of the strand between the snagger and the second-mentioned reeling element is moved by the snagger for severing the strand.

17. A strand takeup apparatus, which comprises a takeup reel, a second takeup reel, means mounting the takeup reels on parallel axes and in transverse alignment with one another, means for rotating the reels in inrunning directions, a distributor traversable between the flanges of the reels, means for locating the distributor in a position in which it guides a strand to the second-mentioned reel along a path in which the portion of the strand between the distributor and that reel is advanced between the flanges of the first-mentioned reel, a snagger having a strand-catching notch formed therein carried with one end of the first-mentioned reel and movable from a position in which the snagger does not project over the more adjacent flange of that reel to a position in which it does project thereover, a cam extending around the longitudinal axis of the reel for holding the snagger in a position not projecting over the more adjacent flange of the first-mentioned reel as the snagger approaches the portion of the strand about to be advanced between the flanges of that reel and for pushing the snagger over the portion of the strand between the flanges of the first-mentioned reel after the snagger has been advanced past the portion of the strand about to be advanced between the flanges of that reel, whereby the snagger catches the strand in the notch therein and moves the portion of the strand between the snagger and the second-mentioned reel laterally, and a cutter for severing the last-mentioned portion of the strand.

18. A strand takeup apparatus, which comprises a takeup reel, a second takeup reel, means mounting the takeup reels on parallel axes and in transverse alignment with one another, means for rotating the reels in inrunning directions, a distributor traversable between the flanges of the reels, means for locating the distributor in a position in which it guides a strand to the second-mentioned reel along a path in which the portion of the strand between the distributor and that reel is advanced between the flanges of the first-mentioned reel, a snagger having a strand-engaging notch formed therein mounted rotatably at one end of the first-mentioned reel and movable from a position in which the snagger does not project over the more adjacent flange of that reel to a position in which it does project thereover, a clutch for connecting the first-mentioned reel to the snagger to rotate the snagger with that reel, means for selectively actuating the clutch, a cam extending around the longitudinal axis of the reel for holding the snagger in a position not projecting over the more adjacent flange of the first-mentioned reel as the

snagger approaches and passes the portion of the strand about to be advanced between the flanges of that reel and for pushing the snagger over the portion of the strand between the flanges of the first-mentioned reel after the snagger has been advanced past the portion of the strand about to be advanced between the flanges of that reel, whereby the snagger catches the strand in the notch therein and moves the portion of the strand between the snagger and the second-mentioned reel laterally, a pair of shear blades mounted in positions in which they receive the strand as it is moved laterally by the snagger, a presser bar for closing the shear blades when moved by the laterally moved portion of the strand, means mounting the shear blades for movement toward either of the reels, and means operable by movement of the blade-mounting means for closing the shear blades.

19. A takeup apparatus, which comprises a rotatable takeup unit, a second rotatable takeup unit, means for rotating the units on parallel axes and for mounting the units in transversely aligned positions, means for guiding a strand past the first-mentioned takeup unit to the second-mentioned takeup unit, a snagger carried with the first-mentioned takeup unit and movable from a position with respect to that unit in which the strand is not engaged thereby to a position in which the strand is snagged thereby, and a cutter over which the strand is moved by the snagger for severing the strand.

20. A takeup apparatus, which comprises a pair of reels mounted in transverse alignment, a guideway extending transversely to longitudinal axes of reels, a guide mounted on the guideway for guiding a strand past one of the reels to the other reel when on one portion of the guideway and for guiding a strand past the last-mentioned reel to the other reel when on a second portion of the guideway, means carried by each of the reels for snagging a strand guided therewith, selectively operable means for actuating the strand-snagging means, and means against which the strand is moved by the strand-snagging means for severing the strand.

21. A takeup apparatus, which comprises a pair of reels mounted in transverse alignment, a guideway extending transverse to longitudinal axes of reels, a distributor traversable substantially parallel to the longitudinal axes of the reels and mounted movably on the guideway for guiding a strand past one of the reels to the other reel when on one portion of the guideway and for guiding a strand past the last-mentioned reel to the other reel when on a second portion of the guideway, a snagger carried by one of the reels for snagging a strand guided past that reel, a second snagger carried by the other reel for snagging a strand carried past that reel, means for actuating the snaggers individually, and means for severing the strand.

22. A takeup apparatus, which comprises a pair of rotatable takeup elements mounted in transverse alignment, a guideway extending transversely to axes of rotation of the takeup element, a guide mounted movably on the guideway for guiding a strand past one of the reels to the other reel when on one portion of the guideway and for guiding a strand past the last-mentioned reel to the other reel when on a second portion of the guideway, means for moving the guide from one of said portions of the guideway, means for moving the guide from one of said portions of the guideway to the other portion thereof, means for

holding the guide at the first-mentioned portion of the guideway, means for holding the guide at the second-mentioned portions of the guideway, means carried by each of the reels for snagging a strand guided therewith, individually operable means for actuating the strand-snagging means, and means for severing a strand snagged by one of the strand-snagging means.

23. A takeup apparatus, which comprises a rotatable reeling element, a second rotatable reeling element, means mounting the reeling elements in transversely aligned positions for rotating the reeling elements selectively and simultaneously in inrunning directions, a rotatable arm mounted pivotally at one end of the first-mentioned reeling element, a snagger carried by the arm and extending substantially parallel to axis of rotation of the first-mentioned reeling element and radially outside that reeling element so that the snagger is projected over that reeling element when the arm is pivoted toward that reeling element, means operable selectively for connecting the snagger to the first-mentioned reeling element to revolve the snagger in a predetermined generally circular path beyond the radial limits of the first-mentioned reeling element, a distributor movable transversely to the axes of rotation of the reeling element for distributing a strand upon the second-mentioned reeling element and for guiding the strand to the second-mentioned reeling element in a plane chordally cutting said path of the snagger, cam means for holding the snagger in a position beyond the near end of the first-mentioned reeling element as the snagger is moved past the portion of the strand entering the portion of the plane chordally intersecting the path of the snagger so that the snagger clears that portion of the strand for moving the snagger to a position extending over the near end of the first-mentioned reeling element after the snagger has been moved past the portion of the strand entering said portion of said plane and before the snagger has been moved to the portion of the strand leaving said portion of said plane and for holding the snagger in the position extending over the near end of the first-mentioned reeling element as the snagger is moved to and past the point at which the strand leaves said portion of the plane so that the snagger catches and grips the strand as the strand is moved past the near end of the first-mentioned reeling element, and a cutter positioned outside the circular path of the snagger in the path in which the portion of the strand between the snagger and the second-mentioned reeling element is moved by the snagger for severing the strand.

24. A takeup apparatus, which comprises a rotatable reeling element, a second rotatable reel-

ing element, means mounting the reeling elements in transversely aligned positions for rotating the reeling elements in inrunning directions, a snagger rotatable with the first-mentioned reeling element and having a snagging portion extending substantially parallel to axis of rotation of the first-mentioned reeling element and radially outside that reeling element, means mounting the snagger for movement relative to the first-mentioned reeling element such that the snagging portion is projected over that reeling element when the snagger is moved toward that reeling element, the snagging portion of the snagger being revolved in a predetermined substantially circular path beyond the radial limits of the first-mentioned reeling element, a distributor for distributing a strand upon the second-mentioned reeling element and for guiding the strand to the second-mentioned reeling element in a plane chordally cutting the path of the snagger, means for holding the snagger in a position in which the snagging portion thereof is beyond the near end of the first-mentioned reeling element as the snagging portion is moved past the portion of the strand entering the portion of the plane chordally intersecting the path of the snagging portion so that the snagging portion clears that portion of the strand, means for moving the snagger to a position in which the snagging portion extends over the near end of the first-mentioned reeling element after the snagging portion has been moved past the portion of the strand entering said portion of said plane and before the snagging portion has been moved to the portion of the strand leaving said portion of said plane and for holding the snagging portion in the position extending over the near end of the first-mentioned reeling element as the snagging portion is moved to and past the point at which the strand leaves said portion of the plane so that the snagging portion catches and grips the strand as the strand is moved past the near end of the first-mentioned reeling element, and a cutter positioned outside the circular path of the snagging portion and in the path in which the portion of the strand between the snagger and the second-mentioned reeling element is moved by the snagger for severing the strand.

DUER C. ROBSON.
